Primary Examiner — Jennifer Rivard*(74) Attorney, Agent, or Firm* — Cheng-Ju Chiang(57) **CLAIM**

The ornamental design for a “hair removal device,” as shown and described.

DESCRIPTION

FIG. 1 is a front, top and left side perspective view of a hair removal device showing my new design;

FIG. 2 is a rear, bottom and right side perspective view of FIG. 1;

FIG. 3 is a front elevational view of FIG. 1;

FIG. 4 is a rear elevational view of FIG. 1;

FIG. 5 is a left side elevational view of FIG. 1;

FIG. 6 is a right side elevational view of FIG. 1;

FIG. 7 is a top plan view of FIG. 1;

FIG. 8 is a bottom plan view of FIG. 1; and,

FIG. 9 is an enlarged view of part 9 of FIG. 4 thereof. The broken lines illustrate portions of the hair removal device that form no part of the claimed design.

The oblique lines represent material that is transparent.
